UNITED STATES PATENT OFFICE.

IGNAC BASINSKI, OF CHICAGO, ILLINOIS, ASSIGNOR OF ONE-FOURTH TO MIKE DUBISH AND ONE-FOURTH TO JOHN BOMBIS, OF CHICAGO, ILLINOIS.

COMPRESSED-AIR MOTOR.

1,065,425.

Specification of Letters Patent. Patented June 24, 1913.

Application filed February 3, 1912. Serial No. 675,269.

To all whom it may concern:

Be it known that I, IGNAC BASINSKI, a subject of the Emperor of Austria-Hungary, residing at Chicago, in the county of Cook 5 and State of Illinois, have invented certain new and useful Improvements in Compressed-Air Motors, of which the following is a specification, reference being had therein to the accompanying drawing.

10 This invention relates to a compressed air motor, and the primary object of my invention is to provide a motor having a storage cylinder that can be charged to operate the motor, until the cylinder is exhausted, 15 whereby the motor can be used for various purposes, particularly where fire would be dangerous in connection with a boiler or where easy access cannot be had to a source of electricity or other source of power.

20 A further object of this invention is to provide a motor wherein a series of air cylinders are employed for imparting a continuous rotary movement to a drive shaft.

With the above and other objects in view, 25 the invention resides in the novel construction, combination and arrangement of parts to be hereinafter specifically described and then claimed.

Reference will now be had to the drawings, wherein:

Figure 1 is a plan of a motor in accordance with this invention, Fig. 2 is a side elevation of the same, Fig. 3 is a longitudinal sectional view of a portion of the motor, 35 Fig. 4 is a cross sectional view of the same, and Fig. 5 is a detail sectional view of one of the air cylinders.

The reference numeral 1 denotes a foundation frame, rectangular in plan and provided with corner pieces 2 and 3 connected by longitudinal girders 4.

Mounted upon the foundation frame 1, between the posts 3, is a large metallic cylinder or tank 5 that has an air inlet pipe 6 45 communicating with a source of air supply provided with a globe valve 7 of the ordinary and well known type. An air pump can be connected to the pipe 6 to pump air into the tank 5 and compress the same therein, the pressure of air within the tank 5 being ascertained by a pressure gage 8 connected to the tank 5, adjacent to the top thereof, said gage being of a conventional form.

55 Arranged upon the foundation frame 1

are transverse bed plates 9 and 10 and mounted upon the former are curved frames 11 having the upper ends thereof connected to the girders 4 and intermediate the ends provided with guides 12. Mounted upon the bed plate 9, beneath the guides 12, are cylinders 13 that have the lower ends thereof connected by pipes 14 to the tank 5, said pipes being in communication with the tank adjacent to the upper end thereof. The 60 pipes 14 have valves 15 of a conventional form that permit of the supply of air to the cylinders 13 being shut off or regulated. One of the cylinders 13 is illustrated in detail in Fig. 5 of the drawings. The cylinder has a piston rod 16, a piston 17, a cylindrical valve casing 18, a valve 19 slidably mounted in said casing and connected to the piston rod 16 by a stem 20. The valve 19 closes a port 21 in the lower end of the cylinder 13 during an upstroke of the piston rod 16, and the port 21 is uncovered during a down stroke of the piston rod to allow air to exhaust from the cylinder. Located upon the pipes 14 are check valves 22 of a conventional form that shut off the supply of air to the cylinders 13 during a down stroke of the piston rod 16.

The piston rods 16 are provided with pitmen 23 and 24. The pitmen 23 are pivotally connected to cranks 25 of a shaft 26, journaled in bearings 27, carried by the girders 4. The pitmen 24 are connected to eccentrics 28 carried by the shaft 27, adjacent to the cranks 25. The shaft 26, intermediate the ends thereof, has a sprocket wheel 29, and the ends of the shaft are provided with balance wheels 30.

Mounted upon the bed plate 10 are vertical posts 31 having brackets 32 supporting a transverse auxiliary tank or cylinder 33. This tank or cylinder is connected to the main tank or cylinder 5 by a pipe 34, said pipe having a globe valve 35 and a check valve 36, both of which are of a conventional form, the latter being of that type that can be set either in an active position or in an inactive position.

Mounted upon the bed plate 10 are cylinders 37 and 38 similar to the cylinders 13. 100 The cylinders 37 are connected to the auxiliary tank 33 by pipes 39 and the cylinders 38 by pipes 40, said pipes having check valves 41 similar to the valves 36.

The cylinders 37 and 38 have piston rods 110

42 and 43 respectively, said piston rods having the upper ends thereof pivotally connected by links 44 and 45 to arms 46 fulcrumed upon the upper ends of posts 47 5 mounted upon the bed plate 10. The upper pivoted ends of the links 44 are pivotally connected by pitmen 48 to levers 49 and 50. These levers are pivotally mounted, as at 60 in the upper ends of the posts 31 and said 10 levers are provided with pitmen 61 that are connected to alternately arranged crank portions 62 of a shaft 63, journaled in bearings 64, carried by the girders 4. The shaft 63 has balance wheels 65 at the ends thereof 15 and a sprocket wheel 66 intermediate the ends. Passing over the wheels 66 and 29 is an endless sprocket chain 67.

Either of the wheels 30 or 65 can be used as a belt wheel for driving machinery by the 20 motor.

The manner in which the cylinders 37 and 38 are arranged is such that the cylinders 37 alternate with the cylinders 38 in transmitting power to the shaft 63, the cylinders 37 25 taking air from the auxiliary tank 33 while the cylinders 38 are exhausting and vice versa. This is also true in connection with the cylinders 13 and all of said cylinders co-operate in transmitting power to the shafts 30 26 and 63, the shafts operating in unison through the medium of the endless sprocket chain 67.

After the main tank 5 has been exhausted, it can be recharged, and the tank is of sufficient size to permit of the motor being operated for a long period of time without recharging, it of course being understood that the exhaust of air from the main tank depends upon the load to which the machine is 40 subjected.

When the tank 5 is charged, the tank 33 is also charged in view of the fact that the valve 35 is opened. In some instances but one set of cylinders is employed to drive 45 both shafts, if so the tank 5 or the tank 33 is closed to that set of cylinders which communicate therewith. When both sets of cylinders are used they are open to their tanks for the supply of air. When the cylinders 37 and 38 are in communication with 50 the tank 33, the latter is in communication

with the tank 5 but the latter is closed to the cylinders 13 if these are not to be utilized, if utilized they are open to the tank 5. It is of course understood that when the load to 55 which the machine is subjected is great, then both sets of cylinders are utilized, but when the load is light only one set of cylinders is employed.

What I claim is:—

1. In an air motor, the combination of a main tank provided with valved means adapted to communicate with a compressed air supply, a pair of shafts, a drive connection between said shafts, an auxiliary tank 65 having a valved supply means communicating with said main tank; a pair of alternately operating fluid pressure operated devices having valved connections with said main tank, a drive connection with one of 70 said shafts, a pair of alternately operated fluid pressure operating devices having valved supply connections with said auxiliary tank and drive connections with the other of said shafts, said shafts arranged 75 above said tanks and devices, and supporting means for said shafts.

2. In an air motor, the combination of a main tank provided with valved means for establishing communication with a compressed air supply, a pair of shafts and a drive connection between said shafts, an auxiliary tank having a valved supply connection with said main tank, a pair of alternately operating fluid pressure operated devices having valved connections with said main tank and a drive connection with one of said shafts, a pair of alternately operating fluid pressure operated devices having valved supply connections with said auxiliary tank, a pair of arms, links for connecting said arms to said second mentioned pair of devices, and drive connections between said arms and the other of said shafts, said shafts arranged above said tanks and devices and supporting means for said shafts.

In testimony whereof I affix my signature in the presence of two witnesses.

IGNAC BASINSKI.
